LUBRICATING SYSTEM.

1,367,677.

Specification of Letters Patent.

Patented Feb. 8, 1921.

Application filed July 24, 1918. Serial No. 246,617.

To all whom it may concern:

Be it known that I, EUGEN WOERNER, a subject of the German Emperor, residing at and whose post-office address is Stuttgart, 5 Militärstrasse 2^B, Germany, have invented certain new and useful Improvements in Lubricating Systems; and I do hereby declare the following to be a full, clear, and exact description of the invention, such as 10 will enable others skilled in the art to which it appertains to make and use the same.

The present invention relates to lubricating systems and particularly to one wherein one or more pumps are actuated by a driving shaft which carries a disk operating the pistons of all the pumps and which also acts as a valve member for the cylinders of all pumps. Heretofore such systems included pumps delivering fresh oil to all the parts to 20 be lubricated. Since some of the pumps sometimes delivered more oil than required, the surplus gradually accumulated and gave rise to trouble. For instance, in internal combustion engines, the surplus oil collected 25 in the crank case, so that, due to the burning of the oil, the engine commenced to smoke. Not only is the burnt oil wasted, but the fresh oil delivered by the pump was spoiled upon mixing with it.

30 The lubricating systems herein disclosed remove this trouble by so providing oil ducts in the driving shaft and in the pump casing, that at least one of the pumps draws off the surplus used oil, and delivers it to a part to 35 be lubricated, or to a filter, or to a reservoir, either without mixture with fresh oil or after mixture with fresh oil in the pump cylinder or in a delivery pipe.

In the accompanying drawings illustrating the invention, Figure 1 is a central vertical section of a multiple pump used in the lubricating systems, showing one of the pistons in its suction stroke; Fig. 2 is a similar view showing the same pump in its delivery 45 stroke; and Figs. 3 to 7 are diagrammatic representations of lubricating systems arranged in various ways in accordance with the invention.

50 The multiple pump has a stationary casing *a* containing a series of pumps arranged in a circle around the driving shaft *b*, which has a worm gear *c* fast to one end and

a cam disk *d* fixed to the other end for reciprocating the pistons of all the pumps.

The casing has for each pump a suction duct, as *f*, leading to the central bore receiving the shaft *b*. This shaft has a duct *g* with suitably arranged terminal portions *g*₁ and *g*₂, and for each pump there is a duct *h* leading to the upper part of the cylinder of 60 the pump *i*, so that as the shaft *b* rotates, communication is established between the source of oil supply connected to *f* and the pump cylinder as the pump piston is pulled downwardly in its suction stroke by the cam disk *d*, as indicated by the arrows in Fig. 1. When the pump piston is moved upwardly in its delivery stroke, the oil is forced out of 65 the top of the cylinder through the duct *h* and the duct *h* of the shaft, and thence 70 through duct *h*₁ and across the reduced portion of the piston into the ducts *l*₂, *l*₁ and *l*, and thence through a delivery pipe to the desired place, as indicated by the arrows in Fig. 2.

75 According to the form given to the cam disk *d*, the piston of each pump may be reciprocated one or more times as desired in each rotation of the shaft *b*, so that by suitably arranging the ducts in the casing *a* and the shaft *b*, the rate at which oil is delivered by the pump and the source from which it is drawn in each suction stroke, and the pipe to which it is delivered in each delivery stroke, may be predetermined.

85 In Fig. 3, the cam disk *d* has one rise and one fall so that each pump is reciprocated up and down once in each rotation of the shaft *b*. In the suction stroke of pump *i*₁, fresh oil is taken from the source *o* through 90 the suction pipe *o*₁ and the suction ducts *e*, *g*₁, *g*, *g*₂ and *h* into the cylinder, while the pump *i* delivers oil to the lower branch of the delivery pipe *m* by way of the ducts *h*₂, *k* and *l*₁, as illustrated at the left-hand side 95 of the figure. Later on in the movement of the shaft *b*, as shown at the right-hand side of the figure, the pump *i*₁, which was previously in its suction stroke, delivers the fresh oil by way of the ducts *h*, *k*₁ and *l*₃ 100 into the upper branch of pipe *m*, while the other pump *i*, which was previously in its delivery stroke, sucks used oil from the source *n* through the pipe *n*₁, ducts *f*, *g*₁,

g, *g*₂ and *h*₂. The fresh oil delivered by the pump *i*₁ and the used oil delivered by the pump *i* mix after the junction of the two branches of pipe *m*, flowing in admixture to 5 any desired place.

In the arrangement of Fig. 4, the cam disk *d* has one rise and one fall as before. In the suction stroke of the pump *i*₁, clean oil is taken from the source *o* through the 10 pipe *o*₁ and ducts *e*, *g*₁, *g*, *g*₂ and *h*₂ at the same time that oil is delivered by the pump *i* through the ducts *h* and *l*₁ into the filter *p* connected to the source *o*. When the duct *g* registers with *f*, as shown in the right-hand 15 part of the figure, fresh oil is taken by the pump *i* from the source of used oil *n* by way of pipe *n*₁, ducts *f*, *g*₁, *g*, *g*₂ and *h*, while the pump *i*₁ is delivering clean oil, taken previously from the source *o*, through the ducts 20 *h*₂, *h*₁ and *l*₂, and thence by way of pipe *m* to any suitable place.

In the arrangement of Fig. 5, the cam disk *d* has two rising portions followed by a single falling portion so that the suction 25 stroke of each piston is divided into two intermittent parts while the delivery stroke is continuous. Thus the pump *i* first draws fresh oil from the source *o* through the pipe *o*₁, ducts *e*, *g*₁, *g*, *g*₂ and *h*, and in the following part of its suction stroke, shown at the right-hand side, draws used oil from the source *n* through the pipe *n*₁, ducts *f*, *g*₁, *g*, *g*₂ and *h*. In the continuous delivery stroke 30 of that pump, the mixed oil from the two sources is discharged through the duct *h* into the delivery pipe, as shown at the upper right-hand part of the second portion of this figure.

In the arrangement of Fig. 6, the cam 40 disk *d* has two rising portions alternating with two falling portions so that each piston is reciprocated twice during each rotation of the shaft *b*. In the position shown at the left of the first portion of the figure, 45 fresh oil is taken from the source *o* by way of the pipe *o*₁, ducts *e*, *g*₁, *g*, *g*₂ and *h*, and in the succeeding delivery stroke is discharged by way of the ducts *h*, *h*₁ and *l*₁ to the pipe *m*. In the second suction stroke of 50 the pump *i*, as shown at the right of the figure, the duct *g*₁ registers with *f*, so that used oil is then drawn from the source *n* through pipe *n*₁, ducts *f*, *g*₁, *g*, *g*₂ and *h*, while on the succeeding delivery stroke, as 55 shown at the upper right-hand part of that portion of the figure, that oil is forced through the ducts *h*, *h*₁ and *l* into the pipe *m*. Thus fresh and used oil are delivered alternately by the pump *i* into a common 60 discharge pipe, wherein those oils mix in flowing to any desired place.

In the arrangement of Fig. 7, the cam disk *d* has two rises and two falls as before. When the duct *g*₁ registers with the duct *e*, 65 as shown by the left-hand portion of the

figure, fresh oil is taken from the source *o* through the pipe *o*₁, ducts *e*, *g*₁, *g*, *g*₂ and *h*, and in the following delivery stroke that pump discharges the oil through the duct *h* into the pipe *m* leading to any suitable place. 70 When the duct *g*₁ registers with the duct *f*, as shown on the right-hand side of the figure, the same pump *i* takes used oil from the source *n* through the pipe *n*₁, ducts *f*, *g*₁, *g*, *g*₂ and *h*, and in the following delivery 75 stroke, delivers that oil through the ducts *r*, *h*₁ and *l*₃ to the pipe *n*₂ leading to the source *o*.

The number of individual pumps or groups of individual pumps used in the arrangements shown above is optional, so that by providing ducts and ports of suitable shape and arrangement, a great variety of modifications, within the scope of the invention, is possible. 80

Having thus described my invention, what I claim is:—

1. In a lubricating system, the combination of a pump, a casing having ducts including inlet and outlet ducts, means for containing fresh oil, means for containing used oil, said inlet ducts being in communication with said means, a shaft rotatably mounted in said casing, said shaft having ducts adapted to register with the ducts in 90 said casing, and a cam disk on said shaft for operating said pump, said shaft rotatable to control communication between said inlet ducts and said pump, whereby said pump draws in used and fresh oil from said oil containing means and delivers said oils to said outlet ducts, said outlet ducts being in communication with said pump. 95

2. In a lubricating system, the combination of a multiple pump having two individual pumps and a casing having ducts including inlet and outlet ducts, means for containing fresh oil, means for containing used oil, said inlet ducts being in communication with said means, a shaft rotatably mounted in said casing, said shaft having ducts adapted to register with the ducts in 100 said casing, and a cam disk fast on said shaft for operating both of said pumps, said shaft rotatable to control communication between said inlet ducts and said pumps whereby said pumps alternately draw in used and fresh oil from said oil containing means and deliver said oils to said outlet ducts, said outlet ducts being in communication with said pumps. 115

3. In a lubricating system, the combination of a multiple pump having two individual pumps, a casing having ducts including inlet and outlet ducts, means for containing fresh oil, means for containing used oil, said inlet ducts being in communication with said means, a shaft rotatably mounted in said casing, said shaft having ducts adapted to register with the ducts in 120

said casing, a cam disk fast on said shaft for operating both of said pumps, said shaft rotatable to control communication between said inlet ducts and said pumps whereby 5 said pumps alternately draw in used and fresh oil from said oil containing means and deliver said oils to said outlet ducts, said outlet ducts being in communication with said pumps, a delivery pipe connecting the 10 outlet duct of one of said pumps to said fresh oil means, and a delivery pipe connecting the outlet duct of the other of said pumps to the machine to be lubricated.

4. In a pump, the combination of a casing, 15 said casing having a piston chamber, a reciprocable piston in said chamber, a

rotatable member in said casing, said casing having ducts including inlet and outlet ducts, said rotatable member having ducts adapted to register with the ducts in said casing for controlling communication between said inlet ducts and said chamber and a cam on said rotatable member adapted to reciprocate said piston, said outlet ducts communicating with said chamber. 20

In testimony whereof I affix my signature, in presence of two witnesses.

EUGEN WOERNER.
